UNITED STATES PATENT OFFICE.

THEODORE A. PRAMHUS, OF DASSEL, MINNESOTA, ASSIGNOR OF ONE-HALF
TO ANDREW G. NORDIN, OF SAME PLACE.

BLINDER-LOOP FOR BRIDLES.

SPECIFICATION forming part of Letters Patent No. 393,658, dated November 27, 1888.

Application filed April 28, 1888. Serial No. 272,151. (No model.)

To all whom it may concern:

Be it known that I, THEODORE A. PRAMHUS, of Dassel, in the county of Meeker and State of Minnesota, have invented certain new and useful Improvements in Blinder-Loops for Bridles, of which the following is a specification.

The object of my invention is to provide an improved blinder-loop for bridles which shall be simple in construction, but very efficient and durable.

In the accompanying drawings, forming a part of this specification, Figure 1 is a side elevation of a portion of a bridle constructed 15 with my improved blinder-loop. Fig. 2 is a vertical section of the same. Fig. 3 is a transverse section on line *x x* of Fig. 1.

In the drawings, 2 represents the cheek-piece, which is preferably formed of cast metal, 20 and is provided with the series of loops 3, 3, arranged at suitable intervals thereon, and at each end with the loops 5, formed preferably substantially in line with the main portion of the cheek-piece. The cheek-piece is also provided near each end, at a point near the base 25 of the loop 5, with a vertical pin, 7, preferably integral with the cheek-piece. The blinder consists, preferably, of a sheet-metal plate, 9, having a sheet of leather, 11, arranged on each 30 side thereof and covering the metal plate.

Both the metal plate 9 and the leather layers 11 extend under the cheek-piece 2. A strap, 13, extends the full length of the cheek-piece on its under side passing under the 35 blinder, as shown in Fig. 2. A series of rivets, 15, extend through the leather strap 13, through the leather layers and the metal plate 9 of the blinder, and through the cheek-piece 2, thus securing all of these parts together, and 40 with the strap 13 covering the cheek-piece upon its under side.

A filling-piece, 17, may be put in at the lower end of the blinder, between the strap 13 and the cheek-piece, as shown in Fig. 2. The 45 strap 13 is long enough preferably to be carried through the upper loop 5, over the upper pin 7, down outside of the cheek-piece, under the loops 3, over the lower pin 7, and through the lower loop 5, thereby covering

the cheek-piece and the ends of the rivets 15. 50 The lower end of the strap 13 is preferably long enough to form the bit-strap, and its end may be carried through the loop 5, over the pin 7, and under one or more of the loops 3. The lower end of the crown-strap 19 will, 55 in a similar manner, be carried through the upper loop 5, over the pin 7, and under the loops 3.

It will be seen that by this means I form a very strong but simple blinder-loop, which 60 may be used with any harness.

If preferred, the blinder may be omitted and the loop without it, as shown and described, be used.

I am aware of the patent to J. W. Weed, of April 30, 1878, No. 203,095, and claim nothing 65 therein shown or described.

I claim as my invention—

1. The combination, with the cheek-piece 2, having the loops 5 and the pins 7 formed integrally therewith upon its upper and lower ends, and having the loops 3, the strap 13, riveted to the under side of said cheek-piece, and having its upper end extending through the upper loop 5, over the upper pin 7, under the loops 3, over the lower pin 7, and through the lower loop 5, and having its lower end adapted to form the bit-strap, substantially as described. 70

2. The combination, with the cheek-piece 2, having the loops 5 and the pins 7 formed integrally therewith upon its upper and lower ends, and having the loops 3, the strap 13, riveted to the under side of said cheek-piece, and having its upper end extending through the upper loop 5, over the upper pin 7, under the loops 3, over the lower pin 7, and through the lower loop 5, and having its lower end adapted to form the bit-strap, and the blinder secured between the strap 13 and the cheek-piece, substantially as described. 80

In testimony whereof I have hereunto set my hand this 30th day of March, 1888.

THEODORE A. PRAMHUS.

In presence of—

W. S. COX,
D. C. STEELE.
